DESIGN FOR A DISPLAY FIGURE

Jules L. Foreman, Scarsdale, N. Y.

Application October 19, 1944, Serial No. 115,850

Term of patent 14 years

(Cl. D80—8)

To all whom it may concern:

Be it known that I, Jules L. Foreman, a citizen of the United States, residing in Scarsdale, in the county of Westchester and State of New York, have invented a new, original, and ornamental Design for a Display Figure or Similar Article, of which the following is a specification, reference being had to the accompanying drawing, forming part thereof.

Fig. 1 is a front perspective view of a display figure or similar article showing my design.

Fig. 2 is the rear perspective view of the display figure shown in Fig. 1.

I claim:

The ornamental design for a display figure or similar article, substantially as shown.

JULES L. FOREMAN.
